Primary Examiner—Jeffrey Asch*Attorney, Agent, or Firm*—Perman & Green, LLP[57] **CLAIM**

The ornamental design for a “display and key array for a telephone handset”, as shown and described.

DESCRIPTION

FIG. 1 is a front, top and right side perspective view of a display and key array for a telephone handset showing our new design;

FIG. 2 is a top elevational view thereof;

FIG. 3 is a front plan view thereof;

FIG. 4 is a right side view thereof;

FIG. 5 is a left side view thereof; and,

FIG. 6 is a rear plan view thereof.
